**COMBINED SCREW DRIVER HOLDER
AND KEY CHAIN**

Sidney Blum, 30 E. 37th St., New York, N.Y.

Filed Aug. 8, 1960, Ser. No. 61,655

Term of patent 14 years.

(Cl. D17—3)

FIG. 1 is a front elevational view of the combined screw driver holder and key chain of the present invention and in which the rear is entirely a flat plain surface.

FIG. 2 is a view of the combined screw driver holder and key chain as shown in FIG. 1 but with the device in one of its open positions for the removal of one of its stored screw driver shanks and insertion thereof in the chuck end of the device as shown in dotted lines;

FIG. 3 is a side elevational view of the combined screw driver holder and key chain;

FIG. 4 is a view of the bottom or chuck end of the combination device; and

FIG. 5 is a view of the top or receptacle end thereof.

The broken line showing of the screw driver blade is for purposes of illustration only.

I claim:

The ornamental design for a combined screw driver holder and key chain, as shown and described.
